United States Patent

Des. 239,457
Patented Apr. 6, 1976

239,457

TOY WHEEL

Richard S. Chesler, Orchard Park, N.Y., assignor to
The Quaker Oats Company, Chicago, Ill.

Filed July 25, 1974, Ser. No. 491,638

Term of patent 14 years

Int. Cl. D21—01

U.S. CL. D34—15 AJ

FIG. 1

FIG. 2

FIG. 3

FIG. 4

FIG. 1 is an end elevational view of a toy wheel showing my new design;

FIG. 2 is a side elevational view thereof;

FIG. 3 is a side elevational view thereof; and

FIG. 4 is a sectional view taken along the line 4—4 in FIG. 3.

I claim:

The ornamental design for a toy wheel, substantially as shown.
